UNITED STATES PATENT OFFICE.

FRANK GERBI, OF NEW YORK, N. Y.

SECTIONAL RADIATOR.

1,282,213.

Specification of Letters Patent.

Patented Oct. 22, 1918.

Application filed April 22, 1914. Serial No. 228,601.

To all whom it may concern:

Be it known that I, FRANK GERBI, a subject of the King of Italy, residing in the city of New York, borough of Manhattan, county and State of New York, have invented certain new and useful Improvements in Sectional Radiators, of which the following is a specification.

This invention pertains to improvements in radiators, particularly radiators built in sections, whereby one or more of the sections thereof may be readily replaced for the purposes of repair, or otherwise. The improved radiator is especially adapted for use on automobiles in conjunction with internal combustion engines of the type used in motor vehicles.

Speaking generally, the salient feature of the invention consists in an improvement in radiators of the type specified, wherein a maximum heat transferring surface is secured, *i. e.*, the hot water from the engine jacket is exposed to a maximum area of air cooled surfaces.

Another feature of the invention consists in means whereby, in cold weather, the exhaust gases from the engine may be utilized to heat said radiator so as to preclude undue chilling or freezing of the cooling liquid.

Features of the invention, other than those described, will appear from the hereinafter detailed description taken in conjunction with the drawings.

In the accompanying drawings I have illustrated one practical embodiment of the invention, but the construction shown therein is to be understood as illustrative only, and not as defining the limits of the invention.

Figure 1 is a transverse section of one half of the radiator of the present invention, said section being taken near the front thereof.

Fig. 2 is a rear elevation of the portion of the radiator shown in Fig. 1.

Fig. 3 is a longitudinal section taken on line 3—3 of Fig. 2.

Fig. 4 is a horizontal section taken on line 4—4 of Fig. 2.

Fig. 5 is a detailed section taken on line 5—5 of Fig. 4.

Fig. 6 is a diagrammatic representation of the system embodying the present invention.

Referring to the drawings, A designates the radiator of the present invention generally, which is formed in a frame a, either as a casting or built up of sheet metal. The frame a is shown in the drawings in the adaptation of the invention to use on an automobile, and in this adaptation, said frame is shaped to conform to the contour of the hood, usually employed to house the motor.

The frame a is preferably hollow throughout its entire extent, and partitions a' divide the interior space thereof into two separate and distinct chambers or spaces. The upper of these chambers B, forms the intake reservoir into which the hot water, as it comes from the jackets of the engine, is fed through the inlet nozzle b. The chamber C, forms the outlet reservoir from which the water, after being cooled in the radiator, is again transmitted to the engine jackets through the outlet c.

The means whereby the water is properly cooled in its passage from the inlet to the outlet reservoir is one of the salient features of this invention, and will next be described.

The frame a is formed with a relatively large air passage therethrough, and through said passage, adjacent to the sides thereof, pass parallel conduits D, D'. These conduits are provided at their rear ends with fingers g², suitably secured to the frame a, whereby the conduits are maintained rigidly in position. At the rear ends of said conduits D, D', are also formed arms d, d', respectively, which overreach and are secured to the exterior of the inlet and outlet reservoirs. The conduits are tubular and the arms d, d', are provided with ducts which open communication between the reservoirs and the channels interior of their adjacent conduits. Said conduits are adapted to support the weight of, and properly position, the several sections of which the radiator is preferably composed.

Each section of the radiator is provided with upper and lower, parallel, tubular members F and F', between which tubular members extends a plurality of tubes. There are two distinct series of these tubes, to wit, the first series G, which extends from the upper to the lower tubular members, and opens communication between the interiors of said members, and the second series g', which are of a smaller diameter than the tubes g, and are arranged interiorly of tubes g.

g. In contradistinction to the tubes g , however, the tubes g' pass through members F , and F' , and are open at their ends to allow air to freely pass therethrough.

5 For the purpose of adding rigidity to the section, parallel strips h , of sheet metal, extend transversely of the section and fit tightly around the tubes g , and these strips h , also serve to carry off, and thus more 10 quickly diffuse the heat in the tubes g , as will hereinafter become apparent.

The opposite ends of each of the tubular members F and F' , are provided with apertures extending therethrough, and these 15 apertures are the same distances between center of the conduits D and D' , respectively. Thus, sections formed as described may readily be passed over the conduits D , D' , and positioned within the frame.

20 According to the present invention, a plurality of these sections are passed over the conduits D , D' , and are adapted to be held rigidly in position, in parallel relation to one another, by means of threaded caps E , E' , which the forward ends of the conduits D , D' are threaded to receive. Washers j are passed over said rods intermediate each section, at the back of the rear section, and at the front of the foremost section. Thus, 25 when the threaded caps E , E' are screwed 30 up tightly, sections of the radiator will be tightly clamped together on the rods, and rattling, due to loose connections, will be precluded.

35 It will be noted, more particularly from Figs. 1, 4 and 5 of the drawings, that, each of the conduits D , D' is cut away at those portions which are interiorly of the tubular members F , F' , when the sections are in 40 proper assembled position within the frame a , and these openings in conduits D are designated in the drawings, (see Figs. 4 and 45 5.) by the reference character l .

It will be manifest from the foregoing description that when the hot water from the jackets of the engine is fed through the inlet nozzle b , of the radiator, into the reservoir B that, when the pump on the engine is operated to pump the cooling fluid 50 through said engine jackets, a suction will be produced in the outlet reservoir C , of the radiator, with the result that the water in the inlet reservoir flows to the outlet reservoir, whence it flows to the engine. The 55 course of passage of the cooling fluid from the inlet reservoir B to the outlet reservoir C , is as follows. The cooling fluid passes through reservoir B , through ducts in the arms d , into the channel within the tubular conduits D , thence to the apertures l , into the upper tubular members F of the several sections. Passing downwardly through the 60 passage intermediate the tubes g , g' , the cooling fluid enters the lower tubular members F' , whence it passes through apertures

into the interior of the rods D' . Flowing rearwardly through the conduits D' , the fluid passes through the duct within the arm d' , whence it flows directly into the outlet reservoir C . During the passage of water 70 through the tubes g , externally of the tubes g' , the movement of the automobile, assisted by a rotary fan, if desired, (not shown) serves to cause air currents to pass through the opening within the frame, and around 75 the tubes g with the result that said tubes are cooled. Furthermore, the heat of the water within said tubes is transmitted to sheet metal strips h , and thereby diffuses with the result that it is more readily carried off by the cold air currents. 80

According to the present invention, the cooling of the water in its passage intermediate the tubes g , g' is further facilitated by passing air currents through the inner 85 tubes g' , and to expedite this the frame a is formed, at the lower part of its central air passage, with a curved face K' , which, when air currents strike the lower portion of the front of the radiator, they are deflected upwardly into the lower open ends of the tubes g' . The upper portion of the frame a is coved, as at K , to allow the ready 90 exit of air from the upper ends of the tubes g' , whence said air is discharged under the 95 hood of the automobile.

It will thus be seen that the water, in its passage from the inlet reservoir B to the outlet reservoir C , through the pipes g , is cooled both internally and externally of 100 said pipes with the result that a greatly increased efficiency in the carrying off of heat units is obtained. This, it will be readily understood, is of distinct advantage, and obviates the necessity of large, cumbersome 105 radiators now usually employed.

It is a recognized difficulty among motorists that in the winter the radiators become frozen, and render the machine inoperative. Various expedients have been resorted to, 110 to obviate this difficulty, but the present invention, by the provision of the inner and outer tubes g , g' , renders possible a simple, yet highly efficient, manner of precluding the freezing of the radiators, even in the 115 most extreme cold weather.

During the summer time the radiator is cooled by atmospheric air which is passed both interiorly and externally of the tubes g , g' , but in the winter time a plate L , shown 120 in dotted lines in Figs. 3 and 4, which forms a part of the equipment, is adapted to be screwed or otherwise secured over the front, lower portion of the frame a , so that the cold atmospheric air is precluded from entering the interior of the tubes g' . A pipe L' is in communication with the chamber behind said plate L , which pipe leads from a valve l , incorporated in the exhaust pipe M , leading from the exhaust manifold of 125 130

the engine. Thus, at the option of the operator of the car, the valve *l* may be manipulated to allow of the passage of the warm waste products of combustion from the engine, through the pipe *L'*, into the chamber rearwardly of the plate *L*, whence these warmed gases pass upwardly through the inner tube *g'*, with the result that said tube is warmed, thereby tempering the action of the cold, atmospheric air, which is in contact with the outer tube *g*, upon the cooling fluid.

Manifestly, therefore, the radiator is adapted to produce maximum efficiency in both warm and extremely cold weather, and cannot be rendered inoperative by degrees of temperature.

Moreover, the building of the radiator in sections allows of ready repair or replacement of any one or a plurality of said sections which may become worn or broken without the necessity of replacing the entire radiator. I wish it understood, however, that I can, if desired, provide the inner and outer tube method of cooling in an integral construction, and that I do not restrict myself to a sectional construction in the claiming of this feature.

It will be apparent from the foregoing description that the present invention embodies numerous important features, which combine to make its structure of high efficiency under widely varying conditions, but, manifestly, I am aware of the fact that analogous structures may be made which would embody some of these features without necessarily employing all.

It will be obvious that various changes in the system as described, as well as in different applications thereof, may be made without departing from the spirit of the invention, so long as they come within the scope of the appended claims.

Having thus fully described the invention, what I claim as new, and desire to secure by Letters Patent is:—

1. An automobile radiator embodying a casing, a hot water intake reservoir positioned in the upper part of the casing, a cold water outlet reservoir positioned in the lower part of the casing, whereby an open space is provided within the casing intermediate said reservoirs, horizontal conduits communicating with said reservoirs and ex-

tending in parallel relation from the backs 55 thereof through the said open space, said conduits being threaded at their free ends and having spaced ports longitudinally of the conduits, in combination with a plurality of separate, independent sections, each 60 of which is provided with upper and lower heads apertured to receive said conduits, circulating tubes extending between the heads, and threaded means, coöperating with the threaded portions of the conduits for detachably locking the section heads upon said conduits with the interior of each head in register with ports in the conduits, whereby said plurality of sections are detachably positioned within said open space to provide 70 circulating pipes between the specified inlet and outlet water reservoirs.

2. An automobile radiator embodying a casing, a hot water intake reservoir positioned in the upper part of the casing, a 75 cold water outlet reservoir positioned in the lower part of the casing, whereby an open space is provided within the casing intermediate said reservoirs, horizontal conduits communicating with said reservoirs and ex- 80 tending in parallel relation from the backs thereof through the said open space, said conduits being threaded at their free ends and having spaced ports longitudinally of the conduits, in combination with a plurality of separate, independent sections, each 85 of which is provided with upper and lower heads apertured to receive said conduits, circulating tubes extending between the heads, threaded means coöperating with the 90 threaded portions of the conduits for detachably locking the section heads upon said conduits with the interior of each head in register with ports in the conduits, whereby said plurality of sections are detachably positioned within said open space to provide 95 circulating pipes between the specified inlet and outlet water reservoirs, and means for directing either cold air or warm air through the circulating tubes connecting the said 100 heads.

In testimony whereof I have signed my name to this specification in the presence of two subscribing witnesses.

FRANK GERBI.
